UNITED STATES PATENT OFFICE.

CHARLES L. BUCKINGHAM AND HENRY C. TOWNSEND, OF NEW YORK, N. Y.

AUTOMATIC CUT-OUT FOR ELECTRIC LAMPS.

SPECIFICATION forming part of Letters Patent No. 296,125, dated April 1, 1884.

Application filed November 19, 1883. (No model.)

To all whom it may concern:

Be it known that we, CHAS. L. BUCKINGHAM and HENRY C. TOWNSEND, citizens of the United States, and residents of New York, in the county of New York and State of New York, have invented certain new and useful Improvements in Automatic Cut-Outs for Electric Lamps, of which the following is a specification.

10 This application we desire to designate as "Case D." In other applications for patent, filed August 15, 1883, we have described and claimed means for enabling the carbons of any one of a series of lamps to be cut out of circuit without causing the cutting out of the other lamps—*i. e.*, means in connection with each lamp whereby a large increase of resistance in the arc of one lamp should cause only that particular lamp and not others to be 15 cut out of circuit. In our application for a patent, designated as "Case B," No. 103,810, filed August 15, 1883, we described a normally-open branch or by-path around the arc of each lamp, which is periodically closed by a circuit-closer operated by clock-work, and an 20 electro-magnet in the arc branch of the lamp, adapted, in case of a high arc resistance at the time of any periodic closing of the by-path, to drop its armature to arrest the periodic circuit-closer and hold the by-path around the 25 arc closed during the continuance of the abnormally high arc resistance. Upon a material decrease of arc resistance enough current is re-established through the coils of the electro-magnet in the arc branch to lift its armature and permit the periodic circuit-closer to 30 continue its rotation and break the circuit of the by-path. In our application designated as "Case C," and also filed August 15, 1883, we have described an arrangement in which 35 we dispense with a locking of the periodic circuit-closer and make the magnet in the arc branch control an independent cut-out or safety branch, the arrangement being such that if the arc resistance be abnormally high when 40 the by-path is completed by the periodic circuit-closer, the magnet in the arc branch will weaken, so that its armature will be drawn back and close a safety branch which does 45 not include the contact-points of the periodic circuit-closer.

Our present invention relates to all apparatus of the class claimed in our prior application, and consisting, generally speaking, of a magnet in the arc branch which controls a 55 safety or branch circuit, and means for periodically closing a by-path or test-circuit of comparatively low resistance around said magnet, and the arc or other translating device.

Our present invention has for its object the 60 simplification of the means hitherto employed by us for periodically closing the branch or by-path around the arc of the lamp. Instead of a clock-work and rotating circuit-closer at each lamp, we now employ an electro-magnet 65 whose coils are in a second and auxiliary line which extends from the central station, where the dynamo-machine for maintaining the lights is located, to each of the lamps. At the central station the auxiliary line is provided with 70 a rotating or other suitable periodic circuit-closer, which derives its motion from the rotating shaft of the dynamo-machine, or from the motor driving the dynamo-machine, or any other convenient source of power. At 75 each periodic closure of the auxiliary line the electro-magnet in said line at each lamp attracts an armature, to which is attached a relay-armature that serves to close the branch or by-path around the arc of the lamp. If 80 the arc resistance of the lamp be great at the closing of the by-path, most of the main-line current will be diverted away from the arc and over the by-path, thus leaving too little current in the arc branch to cause the electro- 85 magnet, whose coils form a part thereof, to hold its armature attracted to its core, whereupon the bar attached to said armature is retracted, thereby locking the armature-lever of the auxiliary line magnet or relay closed upon 90 its front contact and permanently closing the by-path, or, as described in our Case C, closing an extra safety branch during the continuance of a high resistance in the arc branch. It is necessary that the periodic circuit-closing 95 be effected quickly and at considerable intervals apart. As the resistance of the by-path around the arc of the lamps is not great compared with that of the arc branches, it is obvious that if the periodic circuit-closing were 100 much prolonged the lamps would wink, owing to the diversion of current from the arcs; but

if the by-path be closed for not more than a small fraction of a second, there will still be time enough for the relay-armature forming a part of the by-path to be closed and locked in case of a high arc resistance, or, in case of only a normal arc resistance, the diversion of current will be only for so short a time that whatever change—as winking—may actually occur in the light, it will not be perceptible to the eye. Nor is it necessary that the by-path should be closed oftener than once in one or two minutes, for no considerable change in arc resistance could occur during so short an interval. To provide a periodic circuit-closer complying with all of these requirements, we have devised an apparatus for converting a rapid continuous rotation derived from the shaft of the dynamo-machine or other rapidly-rotating body into an infrequent and rather quick movement. To accomplish this result the speed of the prime motor may be reduced to one-fourth by a belt-gear, then to one-fiftieth of the latter by a worm-gear, then to one-tenth of the latter by spur-gearing. The wheel to which such a slow rate of rotation is imparted is large, and has a second segmental set of teeth equal to the number of teeth upon a pinion fixed to the rotating circuit-closer. Thus the circuit-closing wheel will be given an entire rotation, during the rotation of the segment-wheel, through an angle equal to the segment thereof, and the periodic circuit-closing will be effected while the circuit-closing wheel is making a small fraction of a rotation. The circuit-closing wheel preferably is about four inches in diameter, and the contact portion is circumferentially about one-eighth of one inch in length. If the circuit-closing wheel is caused to make a rotation in ten seconds, electrical contact will not be continued longer than about one-eighth of a second. To indicate that the auxiliary line is in working condition, we place a tap-bell magnet in said line at the central station, and upon each periodic closing of the line the bell will be sounded if it be in proper condition. To enable the short-circuiting of the arc branch at any time between the periodic circuit-closing, as in case of the falling out of a carbon, the electro-magnet of the arc branch may have a second armature adapted to close a second by-path around the arc; but this means we do not wish to rely upon in the ordinary operation of the lamp, as those smaller increases of arc resistance which should cause the lamp to be short-circuited would not do so.

We will now describe our invention by reference to the accompanying drawings, forming a part hereof.

Figure 1 is diagrammatic view of our lamp system and means for short-circuiting the arc branches. Fig. 2 shows our periodic circuit-closer. Fig. 3 shows additional means for short-circuiting the arc branch of a lamp without reference to the action of the periodic circuit-closer.

Line L extends from a dynamo-machine or

other generator, and, as shown in Fig. 1, has two lamps, respectively situated at A and B. At point l, line L is divided into two branches, one embracing the carbons c c of the lamp and coils of electro-magnet F, and the other branch forms a normally-open shunt or by-path around the arc. The by-path has its circuit through wire b, stop O', spring O, relay-armature bar H, and resistance R. At points b' 75 b''' an auxiliary wire, L', much finer than L, is connected to L, and at a point near the dynamo a periodic circuit-closer rotates intermittently, and at each rotation brings metallic portion J in contact with contact-brush T. Line L' is provided with an artificial resistance, R², and at each lamp of the system includes the coils of an electro-magnet, E. Upon each rotation of C B, line L' is closed and a short electrical impulse passes over said line. 80 Each impulse upon line L' causes at each lamp armature-bar H to be attracted, thus bringing spring O into contact with anvil O'. During the instant of closing the by-path, whose resistance is considerably greater than that of an arc of normal resistance, some current will be diverted from the arc branch, providing the arc resistance be low; but if the carbons have burned away, so as to interpose a large resistance, a much greater part of current will be 85 diverted from the arc branch through the by-path, thus leaving the current too weak to longer hold armature-bar N against the force of its retracting-spring p, and lever N will be retracted against stop u. Armature-bar H 100 must make its movement as a condition precedent to the backward movement of N; but if N be released at all its end will drop behind H and lock H at or near its front position. By using spring O, which is in metallic connection with H, said lever H may have a slight 105 backward movement toward O', under the influence of spring q, without breaking contact between O' and O. After lever N has locked H to form a contact in the by-path, said by-path will remain closed until the arc resistance shall have been removed, notwithstanding that the line L' may almost instantly be broken by the periodic circuit-closer C B. At the removal of the resistance from the arc 110 branch, however, armature-lever N will be raised and the by-path broken, and again the entire current will flow through the arc branch.

Circuit-closer C B is geared to a constantly-rotating motor from a pulley, P, by a belt, P', wheel Q, worm W, worm-gear wheel X, pinion Y, wheel Z, and sector of gear-teeth U. Wheel Q is four times the diameter of P, and for each rotation of Q wheel X will be given one-fiftieth of a rotation, and ten rotations of Y will 115 effect one rotation of Z. Therefore, if P rotate a thousand times a minute, wheel Z will rotate only once in two minutes. Upon wheel Z, though not in the same plane as the teeth, which gear with pinion Y, is a sector of teeth, 120 U, which gear with the teeth of pinion V, and the teeth of U and V are equal in number.

If the sector U be one-twelfth of a circle, the circuit-closing wheel C B will rotate in ten seconds. Thus the circuit-closing wheel will remain idle during all but one-twelfth of the time, and as the point J may extend over no more than a hundredth part circumferentially of the periphery of C B, J will not remain in contact with T for longer than an eighth or a tenth of a second. By this means a very short 5 and an infrequent contact is effected through the agency of a continuous rotary motion. It is necessary that circuit-closing wheel C B be held in a fixed position when not geared with U, and to that end it is so loaded with a weight, 10 K, that contact J will be held removed from T. M is an electro-magnet in the main line, and M' an electro-magnet in a branch around the arc, and both are for the purpose of feeding the carbons. They, however, have no specific 15 relation to our invention herein claimed.

Fig. 3 illustrates means for effecting a short-circuit or closing of the by-path instantly, and before the periodic circuit-closer can act, in 20 case of a defect in the lamp, as the breaking 25 of the circuit, which would instantly cause the extinguishment of all the lights on the circuit.

The magnet F, instead of controlling a single armature-lever to lock the armature-lever of the by-path closed, has another armature-lever, N', which, with branch b' and stop n', will 30 form a by-path upon a marked weakening of magnetism in F. Until H has first been drawn to a front contact, arm N cannot drop to lock it, as the end of N will rest upon the end of H. Thus the backward movement of N alone 35 is incapable of closing the by-path. N' should be so adjusted as not to operate upon a decrease of magnetism in F, which would drop N.

The tap-bell is operated by an electro-magnet 40 placed in line L', which is magnetized to cause a stroke upon the bell at each closing of said line.

It is obvious that by means of our invention 45 we are enabled to wholly dispense with the fine wire coils now used by many to close a by-path circuit, thus avoiding the danger of their being burned out.

What we claim as our invention is—

1. In an electric lighting system, the combination of a series of electric lamps, each having 50 a shunt or by-path around the arc, and an electro-magnet for closing the same, and a second line-circuit, which embraces the coils of the electro-magnets, for closing said shunts or by-paths.

2. The combination of a main line including the carbons of electric lamps and a normally-open shunt or by-path, an electro-magnet in the arc branch of the lamp, a secondary circuit including an electro-magnet, an armature-lever controlled by the electro-magnet in the secondary circuit, for closing the shunt or by-path, and an armature-lever which is controlled by the electro-magnet in the arc branch, to lock 60 the armature-lever in a position to hold the by-path continually closed.

3. The combination of a main line including the carbons of a series of electric lamps, and a by-path at each lamp, a secondary or main-line circuit which includes the coils of an electro-magnet at each lamp for closing said by-path, and a circuit-closer for said secondary circuit. 70

4. The combination of main line L, having an arc branch and a by-path at a lamp, electro-magnet F, armature-lever N, secondary circuit L', electro-magnet E, armature-lever H, forming a part of the by-path, and circuit-closer C B. 75

5. The combination of an arc branch for an electric lamp, a by-path, armature-lever H, 80 forming a part of the by-path, spring O and contact O', and means for locking armature-lever H at or near front contact.

6. The combination of an arc branch and a by-path for an electric lamp, an armature-lever, 85 H, and spring O, forming a part of the by-path, locking armature-lever N, and electro-magnet F in the arc branch.

7. The combination of an arc branch and a by-path for an electric lamp, a lever forming a 90 part of the by-path, and a locking-lever controlled by an electro-magnet in the arc branch, for locking the by-path lever to permanently close the by-path.

8. The combination of an arc branch and a by-path for an electric lamp, an armature-lever forming a part of the by-path, and a locking-lever controlled by an electro-magnet in the arc branch for holding the lever forming a 95 part of the by-path in a position to close said by-path. 100

9. The combination of a normally-open and intermittently-closed main line, L', including an electro-magnet, E, at each lamp, a circuit-closer at the central station, and a main line, 105 L, including an arc branch and a by-path at each electric lamp, controlled by said electro-magnet.

10. A circuit-closing wheel and an electrical circuit to be closed and broken by said wheel, 110 in combination with means for operating the same, as described, consisting of a continuously-rotating shaft or wheel, and means whereby said wheel only intermittently or periodically gears with the circuit-closing wheel, substantially as described. 115

11. The combination of a motor-pulley, P, a gear-train, a sector gear-wheel, U, circuit-closing wheel C B, pinion V, and an electric circuit which is closed and opened by said circuit-closing wheel. 120

12. The combination of a periodically-rotating circuit-closing wheel, C B, pinion V, gear-sector U, attached to a constantly-rotating train or motor, and an electric circuit which 125 is opened and closed by said circuit-closing wheel.

13. The combination of a circuit-closing wheel, C B, loaded with a weight, K, conducting-spring I, pinion V, gear sector U, and a 130 driving-train.

14. In an electric lamp, the combination of

an arc branch, a by-path, means for closing the same by a periodic circuit-closer, and auxiliary means independent of the periodic circuit-closer for closing a by-path, substantially as specified.

15. The combination of a line-circuit, a periodic circuit closer or breaker therefor, an electro-magnet in the line-circuit for closing a by-path at each lamp of an electric lighting system, and a top or alarm bell at the central station, placed in said circuit.

Signed at New York, in the county of New York and State of New York, this 17th day of November, A. D. 1883.
